UNITED STATES PATENT OFFICE.

WILLARD C. JAMES, OF LOS ANGELES, CALIFORNIA.

FOLDING WALL-BED.

938,668.

Specification of Letters Patent.

Patented Nov. 2, 1909.

Application filed December 18, 1905. Serial No. 292,135.

To all whom it may concern:

Be it known that I, WILLARD C. JAMES, a citizen of the United States, residing at Los Angeles, in the county of Los Angeles and State of California, have invented a new and useful Folding Wall-Bed, of which the following is a specification.

Objects of this invention are:—simplicity of construction, ease of operation, superior concealment in the wall, ready removal from the wall, portability from its recess in the wall to any part of the room; also to provide a convenient folding wall bed having a metal bedstead that folds into a compact space for storage in the wall recess, and that has the appearance of an ordinary metal bedstead when in position for use; to provide a mirror front for the recess when the bed is in use with the same ornamental effect as when the bed is folded in the recess; to provide a safety pivotal support to assist in lowering and raising the bed, and to utilize such support in a satisfactory, convenient and ornamental manner.

Another object is to provide a certain support for the foot of the bed when lowered for use.

Another object is to make a folding bed free of permanent attachment to any fixed frame parts. This bed is particularly adapted for use as a part of a house construction occupying a recess in a wall of an apartment, and its construction is such that it may be set in such recess or removed therefrom without any interference with other parts.

Other objects are to provide means for carrying the bed forward in the act of lowering so that when lowered, the bed will be entirely out of the recess; to allow the recess to be closed by the same closure when the bed is in, as when it is out of use; to provide a folding wall bed that is ordinarily affixed to the building but can be readily detached and removed to and used as a bed in any part of the room; also to provide superior and simple means for moving the bed out fully into the room when lowered into position for use, and for extending and retracting the support as the bed is lowered and raised.

Another object of the invention is to provide a pivotal supporting means which may be used as a couch, shelf, or case of drawers, that is accessible when the bed is folded.

The accompanying drawings illustrate the invention:

Figure 1 is a view of a folding wall bed embodying the invention as it appears when folded into the wall, the shifting fulcrum or pivotal support for the bed being shown without couch upholstering. Fig. 2 is a perspective view of the invention, the shifting fulcrum or pivotal support being constructed with drawers. Fig. 3 is a perspective view of the bed in position for use, omitting bedding. Fig. 4 is a view of the bedstead folded into the wall, the pivotal support therefor being shown in solid lines, with parts in position they occupy while the bed is folded; dotted lines indicate the position of parts when the bed is partially lowered for use. Fig. 5 is a detached, sectional detail showing position of the head of the bedstead when the bed is fully lowered and the head released and brought into upright position. Fig. 6 indicates position of parts intermediate those shown in the solid and dotted lines in Fig. 4. Fig. 7 is a view showing the bed in fully lowered position. Dotted lines indicate the position of the head of the bedstead before the same is released and allowed to come to the position shown in solid lines. Fig. 8 is a fragmental section of the pivoted telescoping head of the bed. Fig. 9 is an enlarged fragmental detail of the counterweight and its connection with the telescopic section of the hinged head of the bed. Fig. 10 is a fragmental elevation viewing the left side of the bed from inside the recess behind the bed while the bed is folded, the parts being in position shown in solid lines in Fig. 4. Dotted lines indicate position occupied by the counterbalance weight when the bed is lowered in position and before the hinged telescopic head of the bed has been released. Fig. 11 is a view of the right side of the head of the bed from similar view-point as Fig. 10 looking right at Fig. 7, showing in solid lines the position of parts just after the bed has been lowered for use and before the hinged portion of the head of the bed has been released. Dotted lines indicate the position the parts occupy in solid lines Fig. 7, after the hinged portion of the head has been released. In this view the foot of the bed is omitted to avoid confusion, but the shifting fulcrum is shown in solid lines. Fig. 12 is a fragmental plan of the foot of the bed in position shown in Fig. 10.

solid lines in Fig. 11, the wall recess being closed by the door. Fig. 13 is a fragmental sectional side elevation showing the construction of the knuckle joint for the legs at 5 the foot of the bed folded. Fig. 14 is a like elevation showing the leg in position for use. Fig. 15 shows the same joint intact viewed from the left of Fig. 14.

1 in a general way designates a bed provided with a base 2 for supporting the bed on end. Means 3 are provided to form a support for the bed when the same is in horizontal position, said means being adapted to form a fulcrum for shifting the bed from upright to horizontal position, and vice versa. The base 2 is fixed to one end of the bed 1, and the fulcrum means or support 3 is constructed to shift as the bed is adjusted from upright to horizontal position, and vice versa. The base 2 is formed in a rocker 4 on which the bed may be rocked forward and backward in the operation of lowering and raising the bed into position for use and stowage. Means are provided for automatically shifting the fulcrum means 3 as the bed is changed from upright to horizontal position, and vice versa. For this purpose the bed is hinged by a hinge 5 to an upright portion 6 of a frame 7 which is provided with a leg 8 having a caster 9 and hinged at 10 to the frame 7 which is also provided with casters 11 and 12. Some or all of the casters 9, 11 and 12 form antifriction supports for the frame 3 whether said frame is in raised or lowered position. On account of the rocker 4 projecting in front of the bed when the bed is up, said rocker is better adapted to cooperate with the means above described to shift forward the fulcrum on which the bed swings.

13 designates brackets fastened respectively to the rails 14 of the bed and carrying a facing 15, which when the bed is upright, 45 forms a partial closure for recess 16 into which the bed is packed for concealment when not in use. The shifting fulcrum support 3 is adapted to serve as a couch or seat, or other desirable article of furniture in front of the recess 16, forming a farther forward extension of the closure for the lower portion of the recess. The leg 8 is adapted to automatically fold into the frame 7 as the fulcrum support 3 shifts outward 55 from the recess in which the bed is stowed when not in use.

17 designates a tie or brace provided with a hook 18 which hooks into a stationary eye 19. When the bed is rocked forward on rocker 4 the hinge attachment 5 between the shifting support 3 and the bed will push the frame 7 away from the mouth of the recess, thus carrying the upper hinged portion of the leg 8 away from the recess, while 65 the tie 17 holds the lower portion of said

leg substantially stationary, thus gradually lowering the frame 7 as the same shifts forward and as the bed lowers. The casters 11 and 12 are arranged at such a distance below the hinge 5 as to come into contact 70 with the floor 20 when the bed-rail 14 is in horizontal position.

21 is a spring-controlled foldable leg hinged by a broken-backed hinge or knuckle joint 22 to the foot 23 of the bed. 24 indicates a spring for holding the broken-backed hinge extended so that the leg 21 stands slightly aslant downward away from the bed-rail, so that when the leg comes to rest on the floor 20, the same can only be folded 80 under the bed by first lifting the foot of the bed. This gives a certain support to the foot of the bed when the bed is lowered.

The bed-frame is formed substantially of iron or suitable metal throughout and is largely of tubular construction comprising tubular longitudinal side bars or rails 14 and angle iron end bars 25 beyond which the rails project fastened together to form a rectangular frame connected by means of 90 fittings 26 with head and foot posts. Head posts 27 extend through said fittings at the head of the bed and are connected by brackets 28 with base shoes or bearing strips 2, the forward end of each shoe being upwardly curved or inclined, as shown at 4, these shoes forming the rear members of the pivotal parallel motion support for the bed frame. The forward members of such support are formed as legs for a couch or other article of furniture, indicated at 7, which is pivotally connected to the said legs at 10 and to the bed frames at 5. The facing 15 is in the form of a cross board or member secured to the front or bottom of 105 the folding bed by bracket 13 attached to the rails 14 at each side of the bed, and the hinges 5 are secured to the bottom of this cross piece or facing 15 and to the top of the board or member 6 which extends along 110 the rear of the couch or member 7 and forms an integral part thereof.

The head board is preferably constructed of corner posts 27, each having a knuckle hinged joint at 33 and upper sections 34 115 which slide on rods 35, and are held toward an upright position by a counterbalance weight 36 that is rigidly connected by rods 37 to dividing rods 38 of the bed head and hangs below the axis of the hinge joint 6. 120

39 designates stops for the extensible head, the same being pins through the rods 35 to engage the sliding sections 34 of the head posts and thereby lift the counterweight at the appropriate time as the bed is lowered for use.

40 is a loop of cord or other flexible connection fastened to the rails 14 to be caught over the head posts to hold the head frame 125 bent to extend parallel with the rails thus 130

to hold the counter balance weight in operative position.

In the upright position or closed position shown in Fig. 4, the bed is supported by the shoes 2. The hinged door or mirror frame 48 and the pivotal means 3, 15 form a closure for the bed containing recess 16 when the bed is folded.

In practical use when the bed is to be lowered the door 48 is first opened, and then the bed is grasped at the foot and drawn outward whereupon the bed frame will rock forward on the rockers 4 causing the frame 7 of the pivotal means to move forward bending down the tops of legs 8, which are held stationary at the bottom by rods 17. The frame 7 finally comes to rest on the casters 11, 12. On further downward movement of the foot of the bed frame the hinge 20 4 becomes the fulcrum on which the bed is carried, as the head end of the frame rises lifting the rocker 4 from the floor and telescoping the rods 35 into head post sections 34, until stops 39 engage the sections 34, whereupon said sections are raised, lifting the counterbalance weight which then swings up on a radius considerably greater than the distance between the pivot at 5 and the weight at any previous time during the operation described. By the telescoping action described the counterbalance weight 36 is given greater leverage for counterbalancing the bed frame and foot when the leverage of the foot is greatest.

In the operation of returning the bed to upright position the extended counterweight 36 reaches the floor after the bed has swung upward considerably on the rocker 4 as indicated in dotted lines in Fig. 6 at a time when the rails are nearing upright position and upon a further upward movement of the foot of the bed; the sections 27 withdraw downward from sections 34 of the head posts leaving the bed free to be easily tilted out of the recess 16 as before. During the initial movement for lowering the bed, the head board 32 sliding on the rods 35 is supported by the weight 36 resting on the floor 20 until the sliding movement is arrested by the stop 39 whereupon the head-board and the weight are carried up as counterweights. The counterweight proper 36 brings the center of gravity of the head board or frame below the pivotal joint 5 thereby tending to hold the head in a vertical position. By releasing the connection 40 the head will come to vertical position. When the bed is in the open position as shown in Figs. 3 and 7, the head board being drawn downward the mirror frame may be swung in place, thus closing the recess above the level concealed by the usual mattress and pillows not shown. By unhooking the rod 17, the bed when down may be detached for removal to any part of the apartment. The foot posts

or legs of the bed at the outer or free end thereof are also preferably made to fold inwardly in order to diminish the depth of the recess required, and means are provided for firmly locking said legs when the bed is down, the construction being preferably such as to give, when the bed is in position for use, an appearance substantially identical with that of a rigid bed foot-frame.

The foot-board or outer end frame of the bed comprises the foot posts 23 secured to fittings 26 and connected by the usual railings 7, said foot posts having extensions 41 to which the legs 21 are pivoted 22. This pivotal connection is such as to allow of a certain amount of longitudinal movement of the members 21, 41 on one another, the extension 41 having a slot 44 in which a pivot pin 45 of the leg 21 turns and travels. The spring 24 ends within the leg 21 and is coiled around a hub or boss 46 on the post extension 41 and bears at its other end against an abutment 47 on said post extension. The leg member 21 has an upward projection or lug 43, and when the said leg is turned into line with the post extension 41 and is then shoved upward longitudinally of said post extension, this lug or projection 43 will ride upwardly within the fitting 26, there being a seat 42 formed in the post extension 41 to receive it. The parts are constructed and arranged to allow the leg to stand aslant as shown in Fig. 7 to avoid folding of the same from pressure that might be accidentally applied thereto.

When the bed is raised in the position shown in Fig. 1, the legs 21 will droop to a more or less nearly vertical position owing to their weight and will readily yield to the action of the closure means for the recess as hereinafter described, and as the bed is lowered the action of gravity, reinforced by the spring 24, will move the leg into line with the post extension 41 slightly oblique to the rail 14, and when the leg strikes the floor this motion will be arrested and the fitting 26 will continue to move downwardly over the same, the projection 43 riding up into the recess 42 within such fitting. This securely locks the leg from movement except on lifting the foot of the bed, thus giving a stable and rigid support and also giving substantially the appearance of an ordinary rigid post or leg when the bed is lowered. A closure means for the recess is desirably provided consisting preferably of a door 48 hinged or pivoted at 49 to one side of the wall 50 of the recess and swinging in to close the upper part of the recess when the bed is either raised or lowered. When the bed is raised said closure will come into close juxtaposition and in the same plane with the cross board or facing member 15 aforesaid on the front of the bed; these two members forming then substantially a continuous

plane closure surface for the front of the recess. The closure board 48 may be provided on its front face with a mirror 51 or may be otherwise ornamented in any suitable manner, and it is preferably provided with means not shown for holding it in closed position.

The shifting fulcrum member 3 may be formed, as aforesaid, as a couch or lounge, being provided with the usual springs and upholstering of such devices and forming, when the bed is in raised position, as shown in Fig. 1, a wall couch or lounge, the back for which is formed by the facing 15. As the bed is lowered, the legs 8 turn forward on their pivots 10 simultaneously with the turning forward of the bed frame on the curved bearings or rockers 4, the member 3 moving forward and downward on these two, centers of movement by a parallel action to position shown in Fig. 3 wherein it is brought close to the floor and underneath the lowered bed, substantially out of the way. In case a couch or lounge is not desired, this member 3 may be formed as any other article of furniture suitable for the purpose; for example, a wall seat, as shown at 3" in Fig. 2 and said seat may be provided with drawers, indicated at 52.

What I claim is:

- 30 1. A bed, a base fixed thereto to support the bed in upright position, said base being formed at its forward end in a rocker, a support pivoted to the bed in front of and above the rocker, and a leg hinged to the support.
- 20 2. A bed provided with a base frame formed in a rocker at its forward end, an adjustable shifting frame hinged to the bed in front and above the rocker, means for automatically lowering and raising said frame as the bed is lowered and raised, and casters supporting said frame in both raised and lowered positions.
- 30 3. A bed, a base fixed thereto to support the same on end and formed in a rocker at one end, said rocker projecting in front of the bed when the bed is up and fulcrum means in front of the rocker for supporting the bed when moved from upright position.
- 40 4. A bed, a base fixed thereto to support the bed in upright position, said base being formed at its forward end in a rocker, a support pivoted to the bed in front of and above the rocker, a leg hinged to the support, and means for holding the foot of the leg stationary.
- 50 5. A bed provided with a base frame formed in a rocker at its forward end, an adjustable shifting frame hinged to the bed in front and above the rocker, and means for automatically lowering and raising said frame as the bed is lowered and raised.

- 65 6. A bed provided with a base formed in

a rocker at its front end, a frame pivoted to the bed above the rocker, a leg hinged to the frame, an eye, and a hook connecting the bottom of the leg with the eye.

7. A recessed body, a bed adapted to fold 70 into the recess thereof, a support for the bed pivotally connected thereto and adapted to move toward and from said body, an adjustable leg for said support, and means for automatically folding said leg to lower 75 said support as the bed is lowered.

8. A bed adapted to fold into a recess, a frame pivoted to the bed and projecting in front thereof and adapted to form a support for the bed when the same is lowered, 80 an adjustable leg for said frame, and means for automatically folding said leg to allow the frame to lower as the bed is lowered.

9. A bed adapted for adjustment to upright and horizontal positions, a support 85 pivoted to said bed and projecting in front thereof to form a couch or the like when the bed is raised, and means including a hinged leg for the support for lowering the support as the bed is lowered. 90

10. A bed holder, a bed adapted to stand upright therein and to lower into a horizontal position, a frame pivoted to said bed and adapted to move toward and from said holder, a leg pivoted to said frame, and a 95 tie connecting said leg with the holder to fold the leg as the frame moves from the holder when the bed is lowered.

11. A bed provided with a pivoted head and adapted for adjustment to upright and 100 horizontal positions, means for holding the pivoted head folded toward the bed frame, and a counter-weight fixed to the head of the bed and arranged to project beyond the pivotal point of said head when the bed is 105 lowered.

12. A bed provided with a head one end of which is pivotally mounted thereon and the other end is free to fold parallel therewith when the bed is horizontal, said head 110 being adapted to move a weight to shift the center of gravity of said bed as the same is brought to and from horizontal or upright position.

13. A bed frame, a shiftable fulcrum 115 adapted to support said frame during the first portion of its movement from horizontal to upright position, a weight to counter-balance the foot of the bed, and an intermittent fulcrum arranged to support the 120 bed frame during the latter portion of its movement from horizontal to upright position.

14. A bed provided with a pivot for swinging said bed for adjustment to upright 125 and horizontal positions, a folding head hinged to said bed, a counter-weight fastened to said head rearward of the bed pivot when the bed is upright and swinging farther rearwardly from the bed pivot when the 130

head is folded than when it is upright, and means for temporarily holding the head in folded position when the bed is down.

15. A bed adapted for adjustment to upright and horizontal positions, and provided with a telescopic head hinged thereto, and a counterweight fastened to said head.

16. A bed frame provided with a pivot for swinging said bed to upright and horizontal 10 positions, a counterweight pivotally connected with the bed, and adapted to project rearwardly of the pivots thereof, means to temporarily hold the weight in such rearward position, a support arranged to support the weight to rest at the close of the upward movement of the bed, a rod to which said weight is fastened, and a section slidably connected with said rod and pivoted to said frame.

20 17. A bed adapted for adjustment to upright and horizontal position, a wall having a recess for the bed, a rocker and base fixed to the head of the bed for supporting the same while tilting and while upright, means 25 for automatically moving the bed into the recess when the bed is erect, legs at the foot of the bed, and means for automatically bringing the legs into supporting position when the bed is lowered, the same being arranged to allow the legs to droop to chamber in the recess when the bed is upright.

18. A pivoted bed provided on its bottom 35 with a facing, a recessed holder therefor, a couch pivoted to the lower portion of the facing and adapted to form a concealment for the lower part of the holder, and a door to form a closure for the recess above the space occupied by the facing when the bed is in the recess, said door being constructed and 40 arranged to swing over the bed when the same is in position to be occupied, said facing and said couch and said door uniting and serving to form a complete closure for the recess when the bed is in the recess.

45 19. A bed adapted for adjustment to upright and horizontal position, a wall having a recess for the bed, a rocker and base fixed to the head of the bed for supporting the same while tilting and while upright, means 50 for automatically moving the bed into the recess when the bed is erect, legs at the foot of the bed, and means for automatically bringing the legs into supporting position when the bed is lowered, the same being arranged to allow the legs to droop to chamber in the recess when the bed is upright, and a closure to close the recess in front of said legs.

55 20. A tilting bed adapted for adjustment

to upright and horizontal position, and provided with sockets at the foot thereof, legs slidably pivoted to the foot of the bed to slide into said sockets to hold the legs rigid when the bed is in horizontal position resting on said legs.

65

21. A bed adapted for adjustment to upright and horizontal position and provided at the foot with spring-actuated legs pivoted by knuckle hinges at the foot of the bed and adapted to slide relative to the bed to come 70 into and out of rigid engagement therewith.

22. A bed frame mounted on a pivotal support and provided with a head pivoted above the level of the frame, a weight on the pivoted head extending on the opposite side 75 of the axis of the pivot from the head frame, and means for detachably holding the head of the bed folded toward the bed-frame.

23. A wall provided with a recess for a bed, a bed provided with a foldable head 80 above its frame at one end and with foldable supports for the foot under its frame at the other end and pivotally mounted to fold into said recess, and a door adapted to close the recess above the level of the frame when the 85 bed is lowered out of the recess and in front of the frame when the bed is folded into the recess.

24. A bed frame provided on its under side with brackets and a facing, a shiftable 90 support for the frame hinged to said facing, means for supporting the frame in upright position, and means for shifting the adjustable support as the frame is tilted from upright to horizontal position, and vice versa. 95

25. A pivoted bed provided on its bottom with a facing, a recessed holder therefor, a couch pivoted to the lower portion of the facing and adapted to form a concealment for the lower part of the holder, and a door 100 arranged outside the recess to form a closure for the recess above the space occupied by the facing when the bed is in the recess, said door being constructed and arranged to swing over the bed when the same is in position to be occupied, thus to allow said recess to be opened and closed when the bed is lowered said facing and said couch and said door uniting and serving to form a closure for the recess when the bed is in the recess. 105 110

In testimony whereof, I have hereunto set my hand at Los Angeles, California, this 9th day of December, 1905.

WILLARD C. JAMES.

In presence of—

JAMES R. TOWNSEND,
JULIA TOWNSEND.
